UNITED STATES PATENT OFFICE.

JOHN H. ROSE, OF NORWALK, CONNECTICUT.

PORTABLE BURGLAR-ALARM.

SPECIFICATION forming part of Letters Patent No. 254,383, dated February 28, 1882.

Application filed November 10, 1881. (No model.)

To all whom it may concern:

Be it known that I, JOHN H. ROSE, of Norwalk, in the county of Fairfield and State of Connecticut, have invented certain new and 5 useful Improvements in Portable Burglar-Alarms, of which the following is a specification.

My invention relates to burglar-alarms which are adapted to be secured to a door-knob or 10 spindle, and comprises alarm apparatus which is set in operation by the turning of the knob-spindle.

The invention consists in the combination, with a hanger adapted to be secured to a door-knob or spindle, and an alarm apparatus suspended therefrom by a pivot, and comprising an escapement-wheel and escapement-anchor for 15 operating the bell-hammer, of an arm extending from said escapement-anchor, and a catch 20 upon the hanger for engaging with said arm to hold the apparatus inoperative. The alarm apparatus may be inclosed in a case which is pivoted to the hanger and the arm on the escapement-anchor may project through an opening 25 in the case.

In the accompanying drawings, Figure 1 represents a front view of the alarm with the front of the case removed and the bell shown only in dotted outline, and Fig. 2 represents a side 30 view with the side of the case removed and the bell in section.

Similar letters of reference designate corresponding parts in both figures.

A designates a hanger, which may consist of 35 a simple casting, and which is represented as made in the shape of a hook adapted to be hung upon the spindle of a door-knob.

The hanger may be secured on the knob-spindle by a clamping-screw, a, so that when 40 the spindle is turned to open the door the hanger will turn with it or be moved transversely.

B designates the case of the alarm apparatus, having an upward extension or arm, B', which is jointed to the hanger A by a pivot, b, so that 45 while the hanger is adapted to turn with the knob-spindle the alarm apparatus will always gravitate downward.

C C designate the two plates of the alarm-movement, which is secured in the case B.

50 D designates the winding-spindle, which is journaled in the plates C C; and D' designates

the spring, one end of which is connected to the winding-spindle D, while the other end is secured to one of the posts e of the movement.

E designates the transmitting-wheel, which is loose upon the winding-spindle D; and d designates a ratchet-wheel, which is fast on the spindle and engages with a pawl, e, on the wheel E, as in common clock-movements, thus enabling the spring to be wound without turning the wheel E. The wheel E gears into a pinion, f, on a spindle, g, which also carries the escapement-wheel F; and h designates the escapement-anchor, which is actuated by the wheel. This escapement-anchor h carries a 65 bell-hammer, i, and also an arm, j, which is vibrated as the escapement-wheel turns and operates the anchor.

G designates a bell or gong, upon which the hammer i strikes, and which is arranged on 70 the front of the case B. The bell G may be, and is here represented as, fixed on the winding-spindle D, and it therefore serves as a handle or key for winding up the spring, and a separate key is dispensed with.

Upon the hanger A, below the pivot b, is a catch, k, which is rigidly attached to the hanger or formed therewith, as here represented. This catch projects outward from the part B', as clearly seen in Fig. 2, and into proximity to 80 the vibrating arm j, and the catch k is slightly notched or depressed on its front, so that the end of the arm j will be retained thereon.

When my alarm is used the spring is wound up, and the end of the vibrating-arm j is sprung 85 outward slightly, so as to bring it in front of the catch k, where it will be retained and the movement prevented from acting. The hanger is then secured upon the knob-spindle of a door or on the knob, if it is adapted thereto.

If the knob is turned by any one attempting to open the door, the hanger A, being clamped on the spindle, will also be turned or moved transversely; but the weight of the alarm apparatus will cause it to turn on the pivot b and always gravitate downward. This movement of the hanger will carry the catch k away from the vibrating arm j and release the latter, and the alarm will thereupon ring until the spring is run down, and cannot be stopped by any 95 one outside the door.

I am aware that alarms or alarm apparatus

have been before suspended by hausers from door-knob spindles, and so constructed as to be set in operation by the turning of the spindles, and I do not therefore claim such an apparatus, 5 broadly.

What I claim as my invention, and desire to secure by Letters Patent, is—

1. The combination, with a hanger and an alarm apparatus suspended therefrom by a pivot, and comprising an escapement-wheel and escapement-anchor for operating a bell-hammer, of an arm extending from said anchor, and a catch upon the hanger for engaging with said arm to hold the alarm apparatus inoperative, substantially as specified. 15

2. The combination of the hanger A, the case B, having the arm B' pivoted to said hanger at b, and containing the movement comprising the escapement-wheel F, the escapement-anchor h, and hammer i, the arm j, projecting from the escapement-anchor through an opening in the case, and the catch k, for engaging with said arm, substantially as specified. 20
